(57) **CLAIM**

The ornamental design for a bread box, as shown and described.

DESCRIPTION

FIG. 1 is a first perspective view of a bread box showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is the folded state of the bread box thereof;

FIG. 10 is the opening state of the bread box thereof; and, FIG. 11 is an enlarged view of the selected portion 11 in FIG.

1.

The dash-dash broken lines shown in the drawings depict portions of the bread box that form no part of the claimed design. The dot-dash broken lines in FIGS. 1 and 11 illustrate the periphery of the enlarged views of the bread box and form no part of the claimed design.

1 Claim, 11 Drawing Sheets
